UNITED STATES PATENT OFFICE.

ERNST KASSNER, OF NEW YORK, N. Y.

DUPLEX ADDING MACHINE AND CASH REGISTER.

Application filed April 30, 1925, Serial No. 26,875, and in Germany May 1, 1924.

The invention relates to a calculating machine or the like with two or more counters, in which an actuating member is shifted through different ranges of movement corresponding with the denomination of the key depressed, and the movement of the actuating member is transmitted by a link to a drive lever pivotally supported between two counters. As the drive lever is shifted to either of two operative positions to bring it into engagement with one or the other of the two counters, it has heretofore occurred that inaccuracies were produced in transmitting the movement of the actuating member to the counters, which inaccuracies increase at higher values in such a manner that at increased speed of actuation, overthrow of the counters was caused.

The object of the invention is to provide equalizing means for correctly transmitting the movement of the actuating member to the drive lever, so that the angular movement thereof is independent of the position to which it may be shifted, and no error will be transmitted to the counters.

The equalizing means consists of a jointed-lever connecting the drive lever with the link. The jointed-lever is also pivoted on a shiftable carrying member on which the drive lever is mounted, so that the jointed-lever is shifted along with the drive lever. In this manner two quadrangles for the transmission of the movement are produced. The smaller one of these quadrangles does not change its shape when the carrying member is shifted from one position to another and only the larger quadrangle is distorted by the shifting between the two operative positions, which distortion does not influence the final results.

An embodiment is shown in the drawings:

Fig. 1 is a fragmentary view showing a cross section through an adding machine;

Fig. 2 shows in larger scale the connection between the actuating member and the drive lever;

Figs. 3 and 4 are diagrams showing the transmission between the two members without and with the insertion of a jointed-lever between the drive lever and the link.

In the embodiment shown, the actuating member 1 (Fig. 1) is controlled by mechanism not shown which connects it with the keys 3 as shown in my copending application filed May 27, 1925, Serial No. 33,156. The actuating member is oscillated by the

shaft 4, in accordance with the denomination of the depressed key 3. A link 6 is pivoted at 2 to the actuating member 1 and is connected at its other end through a series of links to a drive lever 7, which in turn is pivoted at 19 to a carrying member 9, the latter being pivoted to the frame of the machine at 8. Member 7 comprises a segmental gear 18 which is in mesh with an intermediate gear 10, also mounted on said carrying member 9. Through said gear 10 the swinging movement of the actuating member 1 is transmitted to the forward counter or to the rear counter, depending on the position of the member 9. In Fig. 1, the intermediate gear 10 is in engagement with the drive gear 11 of the front counter. The other position, in which the gear 10 is in engagement with the drive member 12 of the rear counter is shown in dotted lines in Fig. 1.

Fig. 3 shows schematically that where link 6 is pivoted directly to drive lever 7 errors are produced in the transmission of the swinging movement of the actuating member to the drive lever 7.

In this figure the solid lines represent the members 1, 6 and 7 in the approximate positions shown in Fig. 1, lever 7 being in its forward position. If member 1 is now moved from its zero position to its "9" position, it takes up the position designated as 1^a, and members 6 and 7 move to positions 6^a and 7^a, causing member 7 to move through a certain angle M. But if, while member 1 is in its zero position, carrying member 9 is shifted to its rear position, member 7 is moved to position 7^b, and upon movement of member 1 to position 1^a as before, members 6 and 7 are caused to move to positions 6^c and 7^c, lever 7 moving through an angle N, which is not the same as angle M, but is smaller by the amount of arc O. The angular movement of lever 7 therefore varies with the position (forward or rear) which the lever is in at the time of actuation of member 1, and a corresponding error is produced in the rotation of member 11 or 12, which error may amount to one unit, especially when the machine is operated at high speed.

The defects arising from a direct connection are according to the present invention eliminated by the introduction of means between the lever 7 and the connecting link 6. This means equalizes the swinging move-

ment of the lever 7 to eliminate the error above discussed, and consists of a jointed-lever 14, 15, connecting the link 6 and the intermediate member 7. The jointed-lever 5 is pivoted at 13 on the carrying member 9 (Figs. 1 and 2) and comprises a lever 14 pivotally supported by frame 9 and pivotally connected to link 6 at 20; and a link 15, the latter being pivoted to said lever 14 10 at 21 and to the intermediate member 7 at 22. As seen in Fig. 4, the solid lines represent members 1, 6, 14 and 7 approximately in the positions shown in Fig. 1, lever 7 being in its forward position. The showing 15 of Fig. 4 does not correspond precisely to Fig. 1 as to the shapes and dimensions of the members, but clearly illustrates the principle involved. If member 1 is now moved from its zero position to its "9" position, it takes up the position designated as 20 1^a, and member 14 is moved through a certain angle P to the position 14^a. But if, while member 1 is in its zero position, carrying member 9 is shifted to its rear position, 25 members 6, 14 and 7 are moved to positions 6^b, 14^b and 7^b, whereupon movement of member 1 to position 1^a causes members 6 and 14 to move to positions 6^c and 14^c, member 14 moving through an angle Q, which is equal 30 to angle P. In all positions, lever 7 is held in parallelism with member 14, so that it moves through the same angle as member 14, with the result that its movement, like that 35 of member 14, is substantially independent of the shifting of the carrying member from forward to rear position and vice versa. The result is that gears 11 and 12 are rotated in equal amounts, this result being chiefly due to the fact that arcs P and Q intersect 40 near their midsections.

As shown in Fig. 2, the provision of the jointed-lever has made it possible to arrange

all pivots in such a manner that the same are moved in circles concentric to the pivot 8 of frame 9, when said frame is swung about 45 its pivot, so that the movement of lever 7 is not influenced any more, when swinging it from one to the other of its end positions.

What I claim is:

1. In a calculating machine, a pair of 50 spaced gears, a pivoted carrying member, a drive lever pivoted to said carrying member and movable therewith to two operative positions, means carried by said carrying member and connected to said drive lever 55 for selectively rotating said gears, and means for oscillating said lever when in either operative position, comprising a link arranged to be moved longitudinally through predetermined distances, a connecting lever pivoted to said carrying member and to said link and substantially parallel with said drive lever, and a second connecting lever pivoted to said first mentioned connecting lever and to said drive lever. 65

2. In a calculating machine, counting mechanism comprising a pair of spaced gears, a drive lever, a carrying member supporting said drive lever and operative to move the same to either of two operative 70 positions, means carried by said carrying member and connected to said drive lever for selectively rotating said gears, and means for oscillating said lever when in either operative position, comprising a link 75 arranged to be moved longitudinally through predetermined distances, a connecting lever pivoted to said carrying member and to said link, and a connection between said connecting lever and said drive lever whereby 80 they are caused to move in unison.

In testimony whereof I affix my signature.

ERNST KASSNER.
